UNITED STATES PATENT OFFICE.

CARL G. NELSON, OF CHICAGO, ILLINOIS.

ELECTRIC SWITCH.

Application filed March 22, 1922. Serial No. 545,674.

To all whom it may concern:

Be it known that I, CARL G. NELSON, a citizen of the United States of America, residing at Chicago, in the county of Cook and State of Illinois, have invented a certain new and useful Improvement in Electric Switches, of which the following is a specification.

This invention relates to that class of manually actuated electric switches in which the reciprocating movement of the push button or plunger is adapted to serially make and break the circuit, and the present improvement has for its object:

15 To provide a structural formation and association of parts in which a single reciprocating push button or plunger is adapted to rock a pivoted switch member alternately in opposite directions to alternately 20 move the contacts of the mechanism into and out of electrical connection, all as will hereinafter more fully appear.

In the accompanying drawings:

Fig. 1, is a central sectional elevation of 25 an electric switch embodying this invention. Fig. 2, is a side elevation in a direction at right angles to Fig. 1, and with parts broken away and in section. Fig. 3, is a horizontal section on line 30 3—3 Fig. 1. Fig. 4, is a perspective view of the movable switch member and its supporting standard in detached condition. Like reference numerals indicate like parts in the 35 several views.

Referring to the drawings, 1 designates the enclosing housing of the switch of any usual and suitable formation and preferably comprising a supporting bottom or base 40 plate 2 of insulating material, a barrel portion or shell 4, and a face or attaching plate 3 as shown, and as usual in the present class of switches.

5 designates a centrally arranged push 45 button or head moving in a guide orifice in the face plate 3, and preferably formed with an expanded guide skirt 6 moving in contact with the inner face of the barrel 4 so as to be additionally guided thereby.

50 7 designates an inwardly extending rib on the barrel 4 and having engagement in a marginal groove in the aforesaid skirt portion 6 of the push button to hold the same against rotation while permitting free reciprocation thereof.

8 designates a depending tubular stem

fixedly secured to the push button 5 with its bore adapted for sliding engagement with a fixed spindle 9 on the base plate 2 aforesaid.

10 designates a coiled spring encircling the spindle 9 and interposed between the base plate 2 and the tubular stem 8 to maintain said stem and the push button 5 in a normal outward position.

11 designates a sleeve rotatively mounted on the inner end of the stem 9 and carrying a laterally extending pin or finger 12 by which the movable switch member is rocked from one position to another, as hereinafter more fully described.

13 designates a terminal bushing secured to the insulated base 2 and carrying a resilient contact member 14 of any ordinary form.

15 designates a companion terminal bushing also secured to the base 2 in insulated relation to the aforesaid bushing 13 and carrying a standard 16 which in the present improvement is provided with a loop portion 17 of an angular form as shown in Figs. 1 and 4, within which the aforesaid lateral pin 12 has play, so that in the final outward movement of the push button 5 and its parts the loop portion 17 is adapted to engage said pin and move the same into proper position for a succeeding operation of the switch mechanism, as said pin reaches the apex of the angular opening of said loop portion 17.

18 designates resilient fingers or prongs 90 on the standard 16 formed with embossed ends 19 for frictional holding engagement with the movable contact member to be described.

20 designates the movable contact member 95 now of a plate form, pivoted at its mid-width to the standard 16 and provided at one side with a lateral contact finger 21 adapted to have intermittent electrical contact with the above described stationary contact member 14. The member 20 is also formed with depressions 22 adjacent to its respective sides, adapted for engagement with one or the other of the embossed ends 19 of the fingers 18 to afford frictional engagement with and hold the movable contact member in either position to which it has been moved.

In the present construction the upper end of the movable member 20 is formed with a 110 centrally arranged V shaped angular extension 23 and with hollow bearing recesses 24

at the respective sides of the contact member and at the base of the inclined faces of the extensions 22, as shown. With the described construction, and in a normal or 5 rest position of the switch parts, the lateral operating pin 12 will in a preceding outward movement, reach the apex of the loop portion 17 and have moved into central transverse relation to the other parts of the 10 mechanism. In such described position of the parts the apex of the V shaped extension 23 of the movable switch member 20 will lay to one side or the other of the transverse central plane of the mechanism, depending 15 upon whether the movable contact finger 21 of said member is in or is out of contact with the stationary contact member 14 aforesaid.

With a downward movement of the push 20 button 5 and the operating pin 12 moving therewith, said pin slides along the inclined portion of the extension 23 which is in its path until said pin reaches the bearing recess 24 at the base of said inclined portion. 25 Further movement of the pin 12 will then rock the movable contact member 20 to move its contact finger 21 into or out of contact with the stationary contact member 14 as the case may be. In such movement of 30 the contact member 20 the apex of the extension 23 will assume a position to the other side of the central transverse plane of the mechanism from that above set forth and be in proper position for a succeeding operation 35 of the mechanisms.

Having thus fully described my invention what I claim as new and desire to secure by Letters Patent, is:—

1. In a switch, the combination of a support, a push button mounted for reciprocation of the support, a lateral operating pin revolubly carried by said push button, a stationary contact member mounted in an insulated manner on the support, a standard 40 mounted in an insulated manner on the support and provided with a loop portion of an angular form adapted for engagement with the aforesaid lateral pin to position the same, a rocking member pivoted on said 45 standard and carrying a contact finger adapted to have contact with the aforesaid stationary contact member, said rocking member having an angular extension at its upper end arranged in the path of the lateral pin aforesaid and side bearing recesses at the base of the inclines of said 50 angular extension, and a spring for moving the push button and associated parts in one direction.

2. In a switch, the combination of a support, a push button mounted for reciprocation on the support and provided with a lateral operating pin, a stationary contact member mounted in an insulated manner on the support, a rocking member pivoted on 55

said standard and carrying a contact finger adapted to have contact with the aforesaid stationary contact member, said rocking member having an angular extension at its upper end arranged in the path of the lateral pin aforesaid and side bearing recesses at the base of the inclines of said angular extension, and a spring for moving the push button and associated parts in one direction, said standard having resilient fingers formed with embossed ends and the rocking member having depressions adapted for frictional engagement with said embossed ends of the resilient fingers. 75

3. In a switch, the combination of a support, a push button mounted for reciprocation on the support, a lateral operating pin revolubly carried by said push button, a stationary contact member mounted in an insulated manner on the support, a standard mounted in an insulated manner on the support and provided with a loop portion of an angular form adapted for engagement with the aforesaid lateral pin to position the same, a rocking member pivoted on said standard and carrying a contact finger adapted to have contact with the aforesaid stationary contact member, said rocking member having an angular extension at its upper end arranged in the path of the lateral pin aforesaid and side bearing recesses at the base of the inclines of said angular extension, and a spring for moving the push button and associated parts in one direction, said standard having resilient 80 fingers formed with embossed ends and the rocking member having depressions adapted for frictional engagement with said embossed ends of the resilient fingers. 85

4. In a switch, the combination of a support comprising a base plate, an attaching plate and an intermediate barrel, a movable push button moving in said attaching plate and having an expanded base portion in

sliding engagement with the inner face of the aforesaid barrel, a stem fixed to and moving with said push button, a lateral pin revolubly carried by said stem, a stationary contact member mounted in an insulated manner on the support, a standard mounted in an insulated manner on the support and provided with a loop portion of an angular form adapted for engagement with the lateral pin to position the same, a rocking member pivoted on said standard and carrying a contact finger adapted to have contact with the aforesaid stationary contact member, said rocking member having an angular extension at its upper end arranged in the path of the aforesaid lateral pin and side bearing recesses at the base of the inclines of said angular extension, and a spring for moving the push button and associated parts in one direction. 110

5. In a switch, the combination of a sup- 115

port comprising a base plate, an attaching plate and an intermediate barrel, a movable push button moving in said attaching plate and having an expanded base portion in 5 sliding engagement with the inner face of the aforesaid barrel, a tubular stem fixed to and moving with the push button, a spindle fixed to the base plate and having guiding engagement in the bore of said tubular stem, 10 a lateral pin moving with said stem, a stationary contact member mounted in an insulated manner on the support, a standard mounted in an insulated manner on the support, a rocking member pivoted on said standard and carrying a contact finger 15 adapted to have contact with the aforesaid stationary contact member, said rocking member having an angular extension at its upper end arranged in the path of the lateral pin aforesaid, and side bearing recesses at the base of the inclines of said angular extension, and a spring for moving the push button and associated parts in one direction.

Signed at Chicago, Illinois, this 18th day 25 of March, 1922.

CARL G. NELSON.
